UNITED STATES PATENT OFFICE.

WILLIAM J. COAKLEY AND LEVI M. ROBBINS, OF ROCKLAND, MAINE.

DESIGN FOR A TEETHING-RING.

SPECIFICATION forming part of Design No. 27,852, dated November 16, 1897.

Application filed October 8, 1897. Serial No. 654,594. Term of patent 14 years.

To all whom it may concern:

Be it known that we, WILLIAM J. COAKLEY and LEVI M. ROBBINS, citizens of the United States, residing at Rockland, Maine, have invented and produced a new and original Design for Teething-Rings, of which the following is a specification.

In the accompanying drawings, Figure 1 is a plan view of the article. Fig. 2 is a view of the other side. Fig. 3 is an edge view.

As shown in the drawings, the leading or material feature of our invention consists of a ring having a projection from the periphery of elongated form and approximately oval in cross-section, the uppersurface being slightly

flattened. The extreme end of the projection has a depressed part of U shape and the under surface of the end is curved toward the top.

What we claim is—

The design for a teething-ring as herein shown and described.

In testimony whereof we affix our signatures in presence of two witnesses.

WILLIAM J. COAKLEY.
LEVI M. ROBBINS.

Witnesses:

WILL IRISH,
ALBERT O. BOWLER.
